UNITED STATES PATENT OFFICE.

WALTER H. HALL, OF WINCHESTER, MASSACHUSETTS, ASSIGNOR TO GOODSPEED MACHINE COMPANY, A CORPORATION OF MASSACHUSETTS.

HEEL-SHAPING MACHINE.

Application filed October 23, 1922. Serial No. 596,194.

To all whom it may concern:

Be it known that I, WALTER H. HALL, a citizen of the United States, residing at Winchendon, in the county of Worcester and State of Massachusetts, have invented a new and useful Heel-Shaping Machine, of which the following is a specification.

This invention relates to a machine particularly designed for shaping the top surface or seat of a wood heel. Such heels are made in a great variety of styles and sizes and their top surfaces are widely varied both as to angle and contour.

It is the general object of my invention to provide a machine for this purpose which shall be entirely automatic in operation and which shall be readily adaptable to heels of widely different characteristics.

A more specific object of my invention is to provide improved devices for clamping and holding a heel during the shaping operation and for automatically actuating the clamping devices in timed relation to the operation of the mechanism by which the heel is presented to the cutter.

A further object of my invention is to provide interchangeable means by which the vertical position of the heel may be varied as desired during the shaping operation.

An important feature of my invention relates to the provision of means for moving the cutter axially, transversely of the heel, as the heel is passed thereunder and for so controlling this axial transverse movement that any desired seat contour may be obtained.

My invention further relates to arrangements and combinations of parts which will be hereinafter described and more particularly pointed out in the appended claims.

A preferred form of the invention is shown in the drawings in which

Fig. 1 is a plan view of my improved machine;

Figs. 2 and 3 are side elevations, looking respectively in the directions of the arrows 2 and 3 in Fig. 1;

Figs. 4 and 5 are rear and front elevations of the machine, looking respectively in the directions of the arrows 4 and 5, in Fig. 1;

Fig. 6 is an enlarged plan view of the heel clamping devices;

Fig. 7 is a detail elevation of the heel rest or support;

Fig. 8 is an elevation of the actuating means for the heel clamping levers;

Fig. 9 is a side elevation of certain actuating parts;

Fig. 10 is a plan view of certain parts, 60 looking in the direction of the arrows 10 in Fig. 5;

Fig. 11 is a detail elevation of a modified cam plate to be described;

Fig. 12 is a plan view of a modified arrangement of the actuating mechanism;

Fig. 13 is a plan view of a cam to be used in the modified structure; and

Fig. 14 is a development of the cam surface thereof.

Referring to the drawings, I have shown a heel shaping machine comprising a frame 10 having bearings 11 (Fig. 5) for a main driving shaft 12. The shaft 12 is provided with a two-step pulley 13 and is driven by 75 a belt 14 operable upon either part of the pulley 13 to provide a relatively high or relatively low speed. A cutter 15 (Fig. 1) is mounted on a spindle or cutter shaft 16 rotatable in bearings 17 on the frame 10. The shaft 16 is provided with a pulley 18 which is driven by a belt 19 from a large drum or pulley 20 (Fig. 3) on the shaft 12.

A guide and tightener pulley 21 is mounted on a bell crank 22 pivoted at 23 on the frame 10. A threaded nut 24 is pivoted to the upper arm of the bell crank 22 and is engaged by an adjusting screw 25 rotatable in a bearing 26 pivoted at 27 to the frame 10. The screw 25 is provided with a hand wheel 28 at the front of the machine by which the tension of the belt 19 may be adjusted as desired.

The cutter spindle or shaft 16 is axially movable in its bearings 17 and is provided with a free collar 30 (Fig. 1) engaged by the forked end 31 (Fig. 3) of a lever 32 pivoted at 33 on a plate 34 which is adjustably secured to a bracket 35 bolted to the frame 10. A hand screw 36 (Fig. 1) is provided for adjusting the plate 34 on the bracket 35 and the adjustment is securely maintained by a clamping screw 37.

At its rear end the lever 32 supports a cam roll 38 positioned to engage a side cam 39 (Fig. 1) mounted on a cam shaft 40. The shaft 40 is mounted in bearings 41 on the frame 10 and may be connected by a clutch through a gear 42, pinion 43 (Fig. 4), intermediate shaft 44, pulley 45 and belt 46.

to a small driving pulley 47 on the main shaft 12.

A tightener pulley 48 (Fig. 2) is mounted on an arm 49 pivoted at 50 to the frame 10 and is controlled by a handle or link 51 pivotally connected to the arm 49 and having a handle 52 at its front end. The link 51 is provided with teeth 53 engaging a lock plate 54 by which the tightener pulley 10 48 may be held in any desired position.

The gear 42 may thus be continuously rotated at relatively slow speed, the gear being loose on the cam shaft 40 and being connected thereto by clutch devices to be now 15 described. Clutch teeth 55 (Fig. 4) are formed on the face of the gear 42 and a stud or plunger 56 is mounted in a clutch casing 57 fixed on the shaft 40 the plunger being 20 yieldingly advanced into the path of the projections 55 by a spring 58. A shoulder 59 on the stud or plunger 56 projects outward through a slot 60 in the casing 57 and is positioned for engagement by a wedge-shaped block 61 when the latter is in raised 25 position.

The block 61 is mounted on a vertical sliding rod 62 and is normally held yieldingly elevated by a spring 63. A cord 64 is connected to the lower end of the rod 62 30 and is directed by a guide pulley 65 (Fig. 2) to a foot lever 66 mounted at the front of the machine.

As the wedge block 61 is normally in raised position, the stud or plunger 56 is 35 normally withdrawn and the shaft 40 is normally at rest. When the foot lever 66 is depressed, however, the wedge block 61 is withdrawn and the plunger 56 is released for engagement by the clutch teeth or 40 projections 55 on the gear 42. If the lever 66 is then immediately released, the shaft 40 will make a single revolution and the plunger 56 will then be again withdrawn to 45 disconnect the shaft from the gear 42. At each such revolution of the shaft 40, the cam 39 and lever 32 act to give the cutter shaft 16 a desired axial movement transversely to the path of movement of the heel which is being formed.

50 A spring 32^a (Fig. 1) is connected at one end to a bearing 17 of the shaft 16 and at the opposite end to the forked lever 32. This spring is relatively heavy and moves the shaft 16 yieldingly in one direction, holding the cam roll 38 firmly against the cam 39.

The heel clamping devices are mounted upon a supporting plate 70 (Fig. 2) pivoted at 71 between arms 72 (Figs. 1 and 2) on a 60 slide or carriage 73 mounted on fixed guide-ways 74. A connecting rod 75 (Fig. 2) is pivoted at one end on a crank pin 76 on a disc 77 fixed on the shaft 40 and the other end of the rod is pivoted at 78 to a 65 plate 79 adjustably mounted on the slide or

carriage 73. The hand screw 80 provides for adjustment of the plate 79 and the adjustment is maintained by a clamping screw 81. The slide 73 is thus reciprocated once for each revolution of the cam shaft 40 and the heel clamping and supporting devices are simultaneously moved back and forth under the cutter 15.

A heel rest or stand 82 (Fig. 7) is pivoted at 83 (Fig. 6) to the supporting plate 70 and is held in desired angular adjustment 75 therein by a pin or stud 84 which may be placed in any one of a series of holes 85 in a depending portion 86 of the stand 82. A stop 87 is adjustably secured to the top of the stand 82 and serves to position the heel H longitudinally in the heel supporting structure.

Heel clamping levers 88 are pivoted at 89 to the support 70 and are provided with 85 removable heel clamping jaws 90 at their forward ends. These jaws 90 are designed to be removed and replaced to adapt the machine for different shapes and sizes of heels. The rear ends of the levers 88 are 90 connected by a spring 91 by which the jaws are yieldingly separated to release the heel, as shown in Fig. 1.

A short shaft 92 (Fig. 8) is rotatably mounted in a vertical position in the slide 95 or carriage 73 and is provided at its upper end with a disc 93 supporting a pair of actuating rolls 94. These rolls engage cam surfaces upon the adjacent inner edges of the clamping levers 88. When the rolls 94 are 100 in the position shown in Fig. 1, the levers are released and the jaws are opened, but when the rolls are moved to the position shown in Fig. 6 the jaws are forced inward to firmly clamp the heel H. 105

For thus actuating the shaft 92 and the rolls 94, the shaft 92 is provided with an arm 95 at its lower end having a roll 96 positioned in an elongated slot 97 (Fig. 10) in a lever 98 pivoted at 99 (Fig. 2) to the frame 10. The free end of the lever 98 is provided with a pivoted block 100 (Fig. 5) through which extends a rod or link 101. The block 100 is yieldingly pressed against a collar 102 on the rod 101 by a spring 103 disposed between the block 100 and a collar 104. The rod 101 is pivotally connected to one arm of a bell crank 105 mounted in a bracket 106 (Fig. 3) upon the frame 10. The lower arm of the bell crank is connected by a link 107 to the lower end of a cam lever 108 pivoted at 109 on the frame 10. 115

A cam roll 110 (Fig. 9) on the lever 108 is positioned for engagement by a cam 111 on the cam shaft 40. A spring 112 (Fig. 3) 125 is connected at one end to the link 107 and at the other end to the frame 10 and acts to hold the cam roll 110 in yielding engagement with the cam 111. The parts are so related that when the cam roll 110 enters 130

the recess 113 (Fig. 9) in the cam 111, the vertical clamping shaft 92 will be turned from the locking position shown in Fig. 6 to the release position shown in Fig. 1.

5 The parts assume this position at that point in the revolution of the cam shaft 40 at which the clutch is disconnected by the action of the wedge block 61.

As previously described, the rear end of 10 the heel supporting plate 70 is pivotally mounted upon the slide or carriage 73. The front end of the plate is provided with a depending projection 115 (Fig. 2) having a roll or stud 116 positioned in the slot 117 15 of a cam plate 118 adapted to be bolted to an adjustable support 119.

Ample provision is made for the adjustment of the cam plate 118 vertically, horizontally and angularly. The support 119 20 is pivoted at 120 on a plate 121 and is provided with a segmental slot 122 through which a clamping bolt 123 extends, this construction permitting angular adjustment of the support 119 on the plate 121. The plate 121 is mounted on a second plate or 25 slide 124 and may be vertically adjusted thereon by a hand screw 125, the adjustment being maintained by a clamping screw 126. The slide 124 may also be horizontally adjusted by a hand screw 127.

With this construction, the cam plate 118 may be adjusted angularly and may be raised or lowered or may be moved to the right or left, thus varying the vertical 30 movement of the heel supporting plate 70 as the carriage 73 is reciprocated. Furthermore, the cam plates 118 may be readily removed and replaced by an interchangeable cam plate 118^a (Fig. 11) having a slot 117^a 35 of any desired contour. A spring 128 (Fig. 2) draws the plate 70 yielding downward and holds the roll 116 continuously against the lower side of the slot 117.

Having described the details of construction of my improved heel shaping machine, I will now briefly describe the operation 40 thereof:—

The machine is designed for shaping the upper surface or seat of a wood heel, the 45 side surfaces of which have been already finished. Assuming that the cam shaft 40 is at rest with the parts positioned as shown in Fig. 1, a heel H is inserted between the clamping jaws 90 and against the stop 87 50 (Fig. 7). The foot lever 66 is then momentarily depressed, engaging the clutch and permitting the cam shaft 40 to make one revolution. As the shaft starts to revolve, the cam roll on the lever 108 (Fig. 9) is 55 immediately forced outward, acting through its described connections to rotate the shaft 92 and force the jaws 90 inward to clamping position. At the same time the connecting rod 75 starts the slide or carriage 73 60 forward under the cutter 15.

As the heel slide is reciprocated under the cutter 15, the contour of the upper surface or seat of the heel is determined by the vertical movement of the heel, as controlled by the cam plate 118, and by the transverse 70 movement of the cutter, as controlled by the cam 39. By a careful design of these cams and by the selection of a suitable cutter, any desired contour of heel seat may be produced. As the revolution of the shaft 75 40 is completed, the slide or carriage 73 is returned to its forward position and the cam roll 110 again enters the recess 113 in the cam 111, releasing the jaws 90 so that the finished heel may be removed and another blank may be substituted therefor.

It is sometimes desirable to give the clamping slide or carriage 73 two complete reciprocations under the cutter 15, at the same time causing the cutter to assume intermediate axial positions in which it will remove any lines or ridges caused by its over-lapping cuts. For this purpose I use the construction shown in Fig. 12 in which a crank shaft 130 is mounted at the rear of the cam shaft 131 and is driven therefrom by gears 132 and 133 at twice the speed of the cam shaft. A crank pin 134 is connected by a link 135 to the carriage 73 as in the previous construction, and thus gives the 90 carriage two reciprocations for each revolution of the cam shaft 131. The speed of the cam shaft is preferably reduced, as by changing the ratio between the gear 136 on the cam shaft and its driving pinion, so that 95 the actual speed of the crank pin 134 is substantially the same as in the form shown in Fig. 4, thus leaving the rate of travel of the carriage 73 unchanged. The cam for moving the cutter shaft may desirably be 100 of the built-up construction shown in Figs. 13 and 14, comprising a cam body 137 to the periphery of which one or more cam plates 138 are adjustably secured by bolts 139. These plates may be made of such 105 shapes as to give any desired series of axial movements to the cutter 15. With the plates as shown in Fig. 14, the cutter will follow the curved outline of the heel along one side, 110 will then return in a substantially straight 115 central path to the starting point, will then follow the opposite curved outline of the heel and will again return along the center, thus removing any ridges caused by the overlapping of the curved side cuts. Any 120 other desired movement may be obtained by adjusting or redesigning the plates 138.

My improved machine is particularly useful on account of its adaptability to operating on heels of a great variety of shapes, sizes and contours, the necessary adjustments being extremely simple and easily performed.

Having thus described my invention, it will be evident that changes and modifica-

tions can be made therein by those skilled in the art within the spirit and scope of my invention as set forth in the claims, and I do not wish to be otherwise limited to the 5 details herein disclosed, but what I claim is:—

1. A heel seat shaping machine comprising a cutter shaft, a cutter thereon, means to rotate said shaft and cutter, a heel clamping device, means to reciprocate said clamping device, and means to reciprocate said cutter shaft transversely to the path of movement of said clamping device and heel. 10
2. A heel seat shaping machine comprising a rotary cutter, a heel clamping device, means to rotate said shaft, automatic means to move said device along a predetermined path, and means to automatically reciprocate said shaft transversely to said path 15 and in definite timed relation to the movement of said clamping device.
3. In a heel seat shaping machine, a rotary cutter, a heel clamping device, means to actuate said device to clamp a heel, means to move said device along a predetermined path adjacent said cutter, and means to move said cutter transversely to the path of movement of said device, said three means being operable in definite timed relation 20 to each other.
4. In a heel seat shaping machine, a cutter, a cutter shaft, a heel clamping device, a cam shaft, a manually controlled clutch by which said shaft may be caused to make a single revolution, means on said cam shaft 25 to reciprocate said clamping device, and cams on said shaft effective to close and open said clamping device, and to reciprocate said cutter shaft axially at each revolution of said cam shaft.
5. In a heel seat shaping machine, a guide-way, a slide mounted thereon, a heel clamping device pivoted on said slide, means to reciprocate said slide, and means to rock 30 said device on said slide as said slide is reciprocated to thereby automatically vary both the elevation of the heel being shaped and the angular position of the heel in relation to the plane of movement of the slide.
6. In a heel seat shaping machine, a guide-way, a slide mounted thereon, a heel clamping device pivoted on said slide, means to reciprocate said slide, a stationary cam plate, and a cam roll associated with said 35 device and engaging said cam plate to rock said device as said slide is reciprocated, said cam plate being both angularly and vertically adjustable to vary the vertical movement of said device.
7. In a heel seat shaping machine, a heel clamping device including a pair of clamp- 40

ing levers, a spring to open said levers, a vertical shaft having a pair of lever-engaging rolls at its upper end and an arm at its lower end, a roll on said arm, a lever pivoted to said machine and having an elongated slot for said roll, and means to move said lever laterally to close said clamping levers and to hold them in closed position. 45

8. In a heel seat shaping machine, a heel clamping device including a pair of clamping levers, a spring to open said levers, a vertical shaft having a pair of lever-engaging rolls at its upper end and an arm at its lower end, a roll on said arm, a lever pivoted to said machine and having an elongated slot for said roll, means to move said lever laterally to close said clamping levers, and means operating simultaneously to reciprocate said clamping device. 50

9. In a heel seat shaping machine, a heel clamping device including a supporting plate, clamping jaws pivoted to said plate, means to move said jaws simultaneously toward each other to clamp a heel, a heel rest pivoted to said plate, and means to hold said rest in different selected vertical positions relative to said supporting plate and clamping jaws. 55

10. In a heel seat shaping machine, a heel clamping device including a heel supporting plate, clamping jaws pivoted to said plate, a heel rest pivoted to said plate, means to hold said rest in selected vertical relation to said plate, means to reciprocate said clamping device, and means to vary the vertical position of said supporting plate as said device is reciprocated. 60

11. A heel seat shaping machine comprising a rotary cutter, a heel clamping device, means to reciprocate said device, means to reciprocate said cutter transversely to the path of movement of said device and in timed relation to such movement, and means to stop the machine after two complete reciprocations of said clamping device. 100

12. A heel seat shaping machine comprising a rotary cutter, a heel clamping device, means to give said device a double complete reciprocation, mechanism including a cam for giving said cutter a predetermined axial movement in fixed relation to the double movement of said clamping device, said cam having detachable cam plates secured thereto by which said axial movement is determined and means to stop the machine after two complete reciprocations of said clamping device. 110

In testimony whereof I have hereunto affixed my signature. 115

WALTER H. HALL.
